UNITED STATES PATENT OFFICE.

ADOLPH P. GUSTAFSON, OF CHICAGO, ILLINOIS, ASSIGNOR TO M. SCHULZ COMPANY,
OF CHICAGO, ILLINOIS, A CORPORATION OF ILLINOIS.

PNEUMATIC ACTION FOR PLAYER PIANOS AND THE LIKE.

1,423,505.

Specification of Letters Patent. Patented July 18, 1922.

Application filed March 1, 1919. Serial No. 280,120.

To all whom it may concern:

Be it known that I, ADOLPH P. GUSTAFSON, a citizen of the United States, residing at Chicago, in the county of Cook and State of Illinois, have invented a certain new and useful Improvement in Pneumatic Actions for Player Pianos and the like, of which the following is a full, clear, concise, and exact description, reference being had 10 to the accompanying drawings, forming a part of this specification:

My invention relates to pneumatic actions for player pianos and the like.

One of the objects of the invention is to 15 provide a practical and efficient pneumatic action of the class specified.

Another object of the invention is to simplify the construction of said action, reducing the complication of the mechanism and 20 the cost of manufacture.

Another object of the invention is to prevent shrinkage of the pouches from interfering with the efficiency of the action.

Another object of the invention is to 25 cure the foregoing and other desirable results in a simple and expeditious manner.

In the accompanying drawings Fig. 1 is a plan view of a portion of a pneumatic action embodying my present invention;

Fig. 2 is a perspective view of one of the 30 power pneumatics of the same;

Fig. 3 is a cross section of the action taken on line 3—3 of Fig. 1;

Fig. 4 is a cross section taken on line 4—4 35 of Fig. 3; and

Figs. 5, 5^a and 6 are views of details of construction.

Referring to the drawings I show in Fig. 1 a portion of a pneumatic action involving 40 a box or casing 1 comprising certain pneumatic mechanism as will be more fully hereinafter pointed out. The action also involves a plurality of power pneumatics 2—2 which are preferably secured to the under side of 45 the box or casing 1, as well shown in Fig. 3. The box or casing 1 is suitably mounted in a player piano or in some other instrument, in accordance with known arrangements by which said box or casing is extended cross- 50 wise of the player piano in front of the piano action, and the pneumatics 2—2 are so disposed that they can operate upon the piano action, as for example by acting

against the sticker 3 thereof, as shown in Fig. 3. 55

The box or casing 1 is provided with a longitudinally extending duct or chamber 4 which is understood to be suitably connected with wind inducing apparatus, as for example by a tubular connection 5, in such a way that a reduced air pressure is continually present in the duct or chamber 4 during the operation of the instrument.

At intervals along the top of the box or casing 1 there are valve chambers 6—6 in 65 which are located valves 7—7, each of these valves 7—7 being located over one of the power pneumatics 2—2. Each valve 7 is provided with a stem or extension 8 which extends down through a duct or passageway 9, which latter communicates with the wind chamber 4, the duct or passage 9 being somewhat larger than the member 8 so as to permit free movement of the latter. The valve 75 stems or members 8 are preferably made of irregular cross section, as for example cross shaped, as shown in Fig. 5, whereby ample opportunity is allowed for the passage of air while at the same time the stem 8 is of sufficient size to hold the valve against undue side movement while permitting a certain amount of vertical movement as is required for its operation. Each valve chamber 6

is substantially closed by a disc member 10 fitted into a correspondingly shaped recess 85 in the top of the box or casing 1 and provided with a central aperture 11 which forms a port affording communication between the chamber 6 and the outside air. The duct or passage 9 also forms a port 90

between the valve chamber 6 and the wind chest chamber 4. These ports 9 and 11 are controlled by the valve 7, said valve 7 closing the port 9 and opening the port 11 when in a lowered position, and opening the port 9 and closing the port 11 when in an upward or elevated position. The valve 7 and stem 8 are connected together by means of a small screw 7^a secured in the stem 8 and passed through a slot in the leather washer 7^b on the bottom of the valve. There is a small space 7^c between the valve 7 and stem 8 to permit relative adjustment or play between valve 95 and stem.

Below each valve 7 and stem 8 there is 105 a pouch arrangement for operating said

valve. In the construction shown this comprises a pouch 12 which is intended to be actuated pneumatically so as to lift the valve 7 by acting upon the stem 8. This pouch 5 12 is extended between two side members 13—13, the pouch 12 being loosely hung so that it has ample play. Mounted upon the pouch 12 as a preferred arrangement is a block or plate 14 preferably made of wood 10 or some similar material. This block or plate 14 is located under the stem 8 of the valve with which the pouch 12 is associated, so that said block 14 will strike and act upon the stem 8 when the pouch is expanded 15 and elevated. The side members 13 are preferably provided by another block 15 which is secured to the top of the pneumatic 2, the box or casing 1 having its bottom provided with a chamber 16 in which said block 20 15 is set. The block 15 is preferably constructed with a channel or recess 17 at the sides of which the members 13 are located, said members 13 projecting upwardly from the floor forming the bottom of said channel 25 or recess, whereby said members 13 form elevations or projections or side walls between which the pouch 12 may be extended and between which there is formed a substantial recess or channel in which said 30 pouch may rest. In this way the pouch 12 may be made very loose and consequently it may shrink, as pouches of this sort do, without doing any harm or impairing the efficiency or effectiveness of the action in the 35 least.

For operating each pouch 12 a tracker board tube 18 is shown, such tube 18 being understood to run to the tracker board in the manner usual in player pianos. This 40

tube 18 is connected with a duct 19 preferably formed in the top or fixed member of the pneumatic 2 and terminated in a port or duct 20 underneath the central portion of the pouch 12 and block 14, whereby the 45 usual variation of air pressure in the tube 18 will cause the actuation of the pouch 12 and thereby the operation of the valve 7.

A bleed arrangement is preferably provided in the block 14, as for example by forming a recess or aperture 21 therein and inserting a nipple 22 in said recess 21, the nipple 22 having a bleed aperture 23 and the pouch 12 having an aperture 24 by which communication may be established through the bleed hole 23, between the vacuum chamber or chest 4, and the pneumatic tube 18. This simplifies the construction and reduces the number of parts and cost of manufacture. 55

The connection is made between the interior of the pneumatic 2 and the valve chamber 6 by means of a port or duct 6^a (Fig. 3), the port 6^a opening into a chamber or recess 25 communicating with the interior of the pneumatic 2. 60 65

In this way the travelling music sheet controls the air pressure in the tube 18 and this in turn effects the operation of the pouch 12 and the latter causes the actuation of the valve 7 so as to open the duct 70 6^a either to the vacuum chest 4 or to the atmosphere, as the case may be, and thereby causes the collapse or expansion of said pneumatic 2 and the consequent operation of the pneumatic sticker 3 and the piano 75 action controlled thereby.

It will be understood that changes and modifications may be made without departing from the spirit of the invention.

What I claim is:

1. A wind chest box or casing having a member provided along its top with valve chambers and along its bottom with pouch chambers, and also having a wind passage or duct extending longitudinally below said valve chambers, valves in said valve chambers, said valves being provided with stems extending down from the valve chambers into said wind passage or duct, pneumatics secured at intervals along the under side 90 of said member and arranged to close said pouch chambers, and pouches mounted on said pneumatics and arranged to cooperate with said valves, the upper members of said pneumatics being provided with ducts or 95 passages adapted for connection with tracker board tubes, said pouches being provided with bleed ports.

2. A wind chest box or casing having a member provided along its top with valve 100 chambers and along its bottom with pouch chambers, and also having a wind passage or duct extending longitudinally below said valve chambers, valves in said valve chambers, said valves being provided with stems 105 extending down from the valve chambers into said wind passage or duct, pneumatics secured at intervals along the under side of said member and arranged to close said pouch chambers, and pouches mounted on 110 said pneumatics and arranged to cooperate with said valves, the upper members of said pneumatics being provided with ducts or passages adapted for connection with tracker board tubes, said pouches being 115 provided with bleed ports, and blocks mounted on said pouches, said blocks being provided with bleed ports adapted to cooperate with said bleed ports in said pouches.

3. In a pneumatic action, the combination of a valve and a pouch for actuating said valve, projecting numbers between which said pouch is extended, said pouch being loose so that it may depend between said 125 members, said pouch being also provided with a block adapted to act upon the valve, said block being provided with an aperture containing a nipple provided with a bleed port, said pouch being provided with an 130

aperture to permit communication with said bleed port.

4. In a pneumatic action, the combination of a valve and a pouch for actuating said valve, projecting members between which said pouch is extended, said pouch being loose so that it may depend between said members, said pouch being also provided with a block adapted to act upon the valve, said block being provided with an aperture containing a nipple provided with a bleed port, said pouch being provided with an aperture to permit communication with said bleed port, said pouch supporting projections being provided by a block which also has an aperture permitting communication with said bleed port.

5. In a pneumatic action, the combination of a valve provided with a downwardly extending valve stem, a block 15 mounted below said valve and having upwardly projecting longitudinally extending side projections 13, a pouch mounted upon said block 15 and extended between the projections 13 thereof, said pouch being loose so as to rest upon the floor between the projections 13, a second block 14 mounted on the pouch 12 and extended lengthwise of the block 15 between the side projections 13 thereof, said block 14 having an aperture provided with a nipple 22 having a bleed port 23, said block 14 being adapted to act upon said valve stem and said pouch and block 15 being provided with apertures permitting communication with the bleed port 15.

6. In a pneumatic action, a valve operating pouch provided with a block having an aperture containing a nipple provided with a bleed port.

7. A pneumatic action having a wind chest box or casing provided with a longitudinally extending member, the top of which is provided with a series of valve chambers formed by recesses in the upper portion of said member, said member being also provided with a longitudinally extending wind passage arranged below said recesses with openings between said recesses and said wind chamber, and being also provided with pouch chambers located below said wind chamber and below the respective valve chambers, valves having heads adapted to fit in said chambers and having stems smaller than said heads and extending through said valve stem openings, a series of pneumatics secured to the under side of said member and adapted to bridge and thereby close said pouch openings and provided on their upper surfaces with pouches cooperating with said valve stems, said pouches being carried by blocks mounted on the upper surface of said pneumatics and extending into said pouch chambers, and other blocks mounted on top of said pouches and below and close to the lower ends of said valve stems.

8. A pneumatic action having a wind

chest box or casing provided with a longitudinally extending member, the top of which is provided with a series of valve chambers formed by recesses in the upper portion of said member, said member being also provided with a longitudinally extending wind passage arranged below said recesses with openings between said recesses and said wind chamber, and being also provided with pouch chambers located below said wind chamber and below the respective valve chambers, valves having heads adapted to fit in said chambers and having stems smaller than said heads and extending through said valve stem openings, a series of pneumatics secured to the under side of said member and adapted to bridge and thereby close said pouch openings, and provided on their upper surfaces with pouches cooperating with said valve stems, said pouches being carried by blocks mounted on the upper surface of said pneumatics and extending into said pouch chambers, and other blocks mounted on top of said pouches and below and close to the lower ends of said valve stems.

9. A pneumatic action having a wind chest box or casing provided with a longitudinally extending member, the top of which is provided with a series of valve chambers formed by recesses in the upper portion of said member, said member being also provided with a longitudinally extending wind passage arranged below said recesses with openings between said recesses and said wind chamber, and being also provided with pouch chambers located below said wind chamber and below the respective valve chambers, valves having heads adapted to fit in said chambers and having stems smaller than said heads and extending through said valve stem openings, a series of pneumatics secured to the under side of said member and adapted to bridge and thereby close said pouch openings, and provided on their upper surfaces with pouches cooperating with said valve stems, said pouches being carried by blocks mounted on the upper surface of said pneumatics and extending into said pouch chambers, and other blocks mounted on top of said pouches and below and close to the lower ends of said valve stems, said lower blocks being elongated and provided with longitudinally and upwardly extending projections at their edges, on which edges said pouches are mounted, and said upper blocks being also elongated and adapted to fit closely between said projections so as to properly seek said upper blocks.

10. A pneumatic action having a hinged pneumatic mounted with its swinging member below its fixed member, said fixed member being provided on its upper surface with an elongated block extending lengthwise of

- said fixed member and provided with upwardly and longitudinally extending projections, a pouch arranged upon said block and having its side edges secured to said longitudinally extending projections, and a second elongated block extending lengthwise of said first mentioned block and mounted on said pouch and adapted to seat between said projections.
10. 11. In a pneumatic action a block having a groove provided with parallel side walls, a pouch covering said groove and a block mounted on the pouch and extending lengthwise of said side walls, said block and pouch being provided with a bleed port.
12. In a pneumatic action a block having a groove provided with parallel side walls, a pouch covering said groove and a block mounted on the pouch and extending lengthwise of said side walls, said last mentioned block being provided with an aperture containing a metallic thimble having a bleed port and the pouch also being provided with an aperture permitting communication with said bleed port.
13. In a pneumatic action a block having a groove provided with parallel side walls, a pouch covering said groove and a block mounted on the pouch and extending lengthwise of said side walls, said last mentioned block being provided with an aperture containing a metallic thimble having a bleed port and the pouch also being provided with an aperture permitting communication with said bleed port, said first mentioned block also having an aperture permitting communication with the bleed port.
14. In a pneumatic action the combination of a block provided with a longitudinally extending groove, a pouch mounted on said block and extending across the groove thereof, said pouch being loose so as to permit it to depend into said groove, and a second block mounted on said pouch and extending lengthwise of the groove thereof, said last mentioned block and pouch being provided with a bleed port.
15. In a pneumatic action the combination of a block provided with a longitudinally extending groove, a pouch mounted on said block and extending across the groove thereof, said pouch being loose so as to permit it to depend into said groove, and a second block mounted on said pouch and extending lengthwise of the groove thereof, said last mentioned block and pouch being provided
- with a bleed port, and said first mentioned block being provided with a duct adapted to communicate with said bleed port.
16. In a pneumatic action the combination of a block provided with a longitudinally extending groove, a pouch mounted on said block and extending across the groove thereof, said pouch being loose so as to permit it to depend into said groove, and a second block mounted on said pouch and extending lengthwise of the groove thereof, said last mentioned block and pouch being provided with a bleed port, and said first mentioned block being provided with a port adapted to communicate with said bleed port, and a power pneumatic on which said first mentioned block is mounted.
17. The combination of a pneumatic and a block mounted on the fixed member of said pneumatic, a pouch mounted on said block, and a second block mounted on said pouch, said second mentioned block being provided with a thimble forming a bleed port and said pouch also being provided with a bleed port, and said fixed member of said pneumatic being provided with a duct adapted for connection with a tracker board tube and extending to said pouch.
18. A wind-way box or casing comprising a member having its top provided with valve chambers and its under side provided with pouch chambers, said member being also provided with a wind duct or passage extending longitudinally below said valve chambers, and a second member fitted into one side of said first mentioned member so as to close that side of said wind duct or passage.
19. A wind chamber box or casing comprising a member provided along its top with valve chambers and along its under side with pouch chambers, and also provided with a wind duct or passage extending longitudinally below said valve chambers and communicating with the same and with said pouch chambers, said valve and pouch chambers and said wind duct or passage being formed by the material of said member, and a second member fitted into one side of said wind duct or passage so as to close said side of the same.
- In witness whereof, I hereunto subscribe my name this 11th day of February, A. D., 1919.

ADOLPH P. GUSTAFSON.
